REFRIGERATOR UNIT MOUNTING

William B. Anderson, Springfield, Mass., assignor
to Westinghouse Electric & Manufacturing
Company, East Pittsburgh, Pa., a corporation
of Pennsylvania

Application September 2, 1938, Serial No. 228,079

5 Claims. (Cl. 62—116)

This invention relates to mechanical refrigerators and more especially to means for supporting and cooling the refrigerant liquefying apparatus of the refrigerator.

5 One object is to support and cool the refrigerant supplying mechanism of a mechanical refrigerator in a novel manner.

Another object is to provide a means for effectively guiding the cooling air over 10 the portions of the apparatus to be cooled.

Another object is to secure the various parts of the refrigerant liquefying apparatus together by a means which also guides the cooling air over the part to be cooled.

15 Another object is to locate the refrigerant apparatus in a noise silencing duct in a manner to effectively circulate the cooling air through this duct.

20 These and other objects are effected by my invention as will be apparent from the following description and claims taken in accordance with the accompanying drawings, forming a part of this application, in which:

25 Fig. 1 is an elevational view of the refrigerator of this invention with substantially the entire side wall broken away to show the interior of the refrigerator;

Fig. 2 is a section on the line II—II of Fig. 1 looking in the direction of the arrows;

30 Fig. 3 is a section on the line III—III of Fig. 1 looking in the direction of the arrows;

Fig. 4 is a plan view of the base plate of the refrigerant liquefying apparatus;

35 Fig. 5 is a section on the line V—V of Fig. 4 looking in the direction of the arrows; and

Fig. 6 is a section on the line VI—VI of Fig. 4 looking in the direction of the arrows.

40 Referring now more particularly to Fig. 1, the reference numeral 10 identifies a cabinet having an outer casing 11 and a horizontal partition 12 therein which divides the cabinet 10 into a food compartment 13 and a machine compartment 14. The food compartment 13 is lined with insulating material 16 and is provided with an inner liner 17. An evaporator or cooling unit 18 is secured to 45 the upper wall thereof. Access to this compartment may be had through a door 19 which is adapted to swing on hinges 21.

45 The lower edges of the refrigerator casing 11 are rolled inwardly to form flanges 22 which rest on a base section 23 comprising a rectangular metal frame 24, the upper and lower edges of which are bent inwardly to form flanges 20. An opening 26 is formed in the rear wall of the frame 24. Secured on the inturned flanges 22 of the

outer casing of the refrigerator cabinet by means of the bolts 27, which also pass through the upper flanges 20 of the base section 23, is a metal plate 28, shown in greater detail in Figs. 4, 5, and 6. The plate 28 is of substantially rectangular form and has a portion 29 cut out in one of the shorter edges. The other three edges of plate 28 are turned upwardly to form reenforcing flanges 30. A reenforcing groove 31 is pressed downwardly in the plate near its center and parallel to the shorter edges. A reenforcing panel 32 is also pressed upwardly near the short flanged edge of the plate. Holes 33 in the plate provide for the passage of bolts 27 therethrough. Plate 28 forms the bottom of cabinet. 5

10 A refrigerant liquefying apparatus 34 is mounted on the plate by means of springs 35 and hold-down bolts 40. The refrigerant liquefying apparatus 34 comprises a sealed casing 36 in which is housed the refrigerant compressor and the motor 20 for driving the same. The compressor and the motor are of conventional design and are not shown on the drawings. U-shaped fins 37 are welded to the portion of the casing 36 containing the motor and a metal shroud 38 is welded at one 25 of its edges to the extremities of the projecting U-shaped fins 37 on the casing 36. The other end of the shroud 38 diverges and is secured to the edges of a rectangular condenser 39. The condenser 39 is also of conventional design and comprises a radiator which dissipates the heat of 30 the compressed refrigerant vapor. 35

Fig. 2 is a section on the line II—II of Fig. 1 looking in the direction of the arrows;

40 Fig. 3 is a section on the line III—III of Fig. 1 looking in the direction of the arrows;

45 Fig. 4 is a plan view of the base plate of the refrigerant liquefying apparatus;

50 Fig. 5 is a section on the line V—V of Fig. 4 looking in the direction of the arrows; and

55 Fig. 6 is a section on the line VI—VI of Fig. 4 looking in the direction of the arrows.

Referring now more particularly to Fig. 1, the reference numeral 10 identifies a cabinet having an outer casing 11 and a horizontal partition 12 therein which divides the cabinet 10 into a food compartment 13 and a machine compartment 14. The food compartment 13 is lined with insulating material 16 and is provided with an inner liner 17. An evaporator or cooling unit 18 is secured to 45 the upper wall thereof. Access to this compartment may be had through a door 19 which is adapted to swing on hinges 21.

The lower edges of the refrigerator casing 11 are rolled inwardly to form flanges 22 which rest on a base section 23 comprising a rectangular metal frame 24, the upper and lower edges of which are bent inwardly to form flanges 20. An opening 26 is formed in the rear wall of the frame 24. Secured on the inturned flanges 22 of the

outer casing of the refrigerator cabinet by means of the bolts 27, which also pass through the upper flanges 20 of the base section 23, is a metal plate 28, shown in greater detail in Figs. 4, 5, and 6. The plate 28 is of substantially rectangular form and has a portion 29 cut out in one of the shorter edges. The other three edges of plate 28 are turned upwardly to form reenforcing flanges 30. A reenforcing groove 31 is pressed downwardly in the plate near its center and parallel to the shorter edges. A reenforcing panel 32 is also pressed upwardly near the short flanged edge of the plate. Holes 33 in the plate provide for the passage of bolts 27 therethrough. Plate 28 forms the bottom of cabinet. 5

A refrigerant liquefying apparatus 34 is mounted on the plate 28 by means of springs 35 and hold-down bolts 40. The refrigerant liquefying apparatus 34 comprises a sealed casing 36 in which is housed the refrigerant compressor and the motor 20 for driving the same. The compressor and the motor are of conventional design and are not shown on the drawings. U-shaped fins 37 are welded to the portion of the casing 36 containing the motor and a metal shroud 38 is welded at one 25 of its edges to the extremities of the projecting U-shaped fins 37 on the casing 36. The other end of the shroud 38 diverges and is secured to the edges of a rectangular condenser 39. The condenser 39 is also of conventional design and comprises a radiator which dissipates the heat of 30 the compressed refrigerant vapor. 35

Fig. 2 is a section on the line II—II of Fig. 1 looking in the direction of the arrows;

40 Fig. 3 is a section on the line III—III of Fig. 1 looking in the direction of the arrows;

45 Fig. 4 is a plan view of the base plate of the refrigerant liquefying apparatus;

50 Fig. 5 is a section on the line V—V of Fig. 4 looking in the direction of the arrows; and

55 Fig. 6 is a section on the line VI—VI of Fig. 4 looking in the direction of the arrows.

Referring now more particularly to Fig. 1, the reference numeral 10 identifies a cabinet having an outer casing 11 and a horizontal partition 12 therein which divides the cabinet 10 into a food compartment 13 and a machine compartment 14. The food compartment 13 is lined with insulating material 16 and is provided with an inner liner 17. An evaporator or cooling unit 18 is secured to 45 the upper wall thereof. Access to this compartment may be had through a door 19 which is adapted to swing on hinges 21.

The lower edges of the refrigerator casing 11 are rolled inwardly to form flanges 22 which rest on a base section 23 comprising a rectangular metal frame 24, the upper and lower edges of which are bent inwardly to form flanges 20. An opening 26 is formed in the rear wall of the frame 24. Secured on the inturned flanges 22 of the

duct. An opening 45 is also formed in the front wall of the machine compartment to permit the cleaning of the condenser 39. This opening is closed by an ornamental cover 49.

5 Both the entrance 26 and the exit to the air circulating duct are located in the rear wall of the refrigerator which wall is normally turned to a wall of the room wherein the refrigerator is located. This results in damping the noise 10 of the compressor. The air circulating duct may be lined with noise deadening material to further damp the noise from the compressor.

15 The refrigerant liquefying apparatus 34 communicates with the evaporator 18 through a suction tube 46 connecting the top of the evaporator 18 and the casing 36 and a capillary impedance tube 47 connecting the bottom of the condenser 39 and the bottom of the evaporator 18. A tube also connects the casing 36 with the condenser 39 to convey the compressed refrigerant vapor to the latter.

20 The tubes 46 and 47 are led through the opening 43 in the rear of the machine compartment 14, through the air duct 44, and through a second opening 48 in the rear of the food compartment 13. The opening 48 is sufficiently large to permit the insertion of the evaporator 18 therethrough so that the entire refrigerating apparatus comprising the refrigerant liquefying unit 34, the evaporator 18 and the connecting tubes 46 and 47 may be secured in place without disconnecting the tubes 46 and 47.

25 The opening is closed with a removable inner plate 51 secured to the inner liner 17 by means of the lugs 52 and the bolts 53 and with an outer closing plate 54 secured to the refrigerator casing 11 by means of the bolts 56. Insulating material 57 is packed between the two plates 51 and 54.

30 40 It will be apparent from the foregoing that this invention provides an integral refrigerant liquefying unit the structural parts of which are shaped to direct the cooling air over the part to be cooled. This unit is furthermore housed and supported in an air duct in a manner to insure a positive circulation of the air through the duct.

35 50 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

55 What I claim is:

1. In a mechanical refrigerator, the combination of a machine compartment having an upper and a lower opening in its rear wall, a horizontal plate in said compartment located between said openings, a notched-out portion in said plate toward the front of said machine compartment to define an air duct from said lower opening, 60 underneath said plate, through the notch in said plate, over said plate, and through said opening,

and a refrigerant liquefying apparatus on said plate and adapted to be cooled by the air flowing through said duct.

2. In a mechanical refrigerator, the combination of a machine compartment having an upper 5 and a lower opening in its rear wall, a horizontal reinforced metallic plate in said compartment located between said openings, a notched-out portion in said plate toward the front of said machine compartment to define an air duct 10 from said lower opening, underneath said plate, through the notch in said plate, over said plate, and through said opening, and a refrigerant liquefying apparatus on said plate and adapted to be cooled by the air flowing through said duct. 15

3. In a machine compartment of a refrigerator, an air duct therein having an entrance and an exit spaced from said entrance, a refrigerant liquefying apparatus in said air duct, said refrigerant liquefying apparatus comprising a 20 casing containing a compressor unit, a condenser, an air circulating fan, and a shroud, said shroud being adapted and arranged to unite said casing, said condenser, and said fan into a unitary structure and guide the air currents set up by 25 said fan through the condenser and over said casing, said refrigerant liquefying apparatus being positioned in said duct to draw air through the entrance and expel it through the exit thereof. 30

4. In a refrigerator, in combination, a machine compartment, said compartment forming an air duct having an entrance and an exit, said entrance being remote and below the exit of said air duct, a refrigerant liquefying apparatus in 35 said duct, said refrigerant liquefying apparatus comprising a motor and a compressor housed in a sealed casing, radiating fins on the walls of said casing adjacent the motor, a shroud, one end of which surrounds said radiating fins and 40 is connected thereto, a condenser secured in the other end of said shroud, a fan in said shroud for drawing air through the condenser and blowing it through the shroud over the radiating fins, said condenser, shroud, fan, and compressor 45 being located in the air duct of said machine compartment in a manner to draw air through the entrance end and expel it through the exit end of said duct. 50

5. In a refrigerator, the combination of a machine compartment forming an air duct, a plate forming a baffle in said duct, and a refrigerant liquefying unit on said plate, said refrigerant liquefying unit comprising a refrigerant condenser substantially sealed in said air duct, said refrigerant condenser having transverse air passages, a fan for blowing air through said duct and through said air passages, a casing in said duct, said casing containing a motor compressor unit and a shroud for directing the air flowing through the air passages of the condenser over the casing, said shroud also holding said condenser and casing in spaced relationship. 55 60
